Inventor:

Joseph Selinger
By *Lucile Selinger*
Attorney.

UNITED STATES PATENT OFFICE.

JOSEPH SELINGER, OF OBERSTEINMAUR, SWITZERLAND.

HANDLE HOLDER.

Application filed March 31, 1921. Serial No. 457,458.

(GRANTED UNDER THE PROVISIONS OF THE ACT OF MARCH 3, 1921, 41 STAT. L., 1313.)

To all whom it may concern:

Be it known that I, JOSEPH SELINGER, a citizen of Switzerland, residing at Obersteinmaur, in the Canton of Zurich and State 5 of Switzerland, have invented certain new and useful Improvements in Handle Holders (for which I have filed application in Switzerland, Nov. 8, 1919, Patent No. 86,008), of which the following is a specification.

10 My invention consists in an improved handle-holder for floor-brushes, brooms and the like, comprising at least two oblong guiding elements which, between their extremities, are loosely connected by at least one 15 connecting member in such a manner as to rock about this member.

On the accompanying drawing, Fig. 1 is an elevation of one embodiment of the invention, shown with a handle inserted thereinto and applied to a brush-body. Fig. 2 is a sectional view taken along the line A—B in Fig. 1, without the handle; Fig. 3 is a view taken from beneath the holder. Figs. 25 4 and 5 are, respectively, a side elevation of a modified form of holder, and a section on line 5—5 of Fig. 4.

a represents the two guiding-elements forming each a part of a conic surface. They are provided each with an eye c on 30 their outside, a ring b loosely connecting said elements a being inserted into these eyes. The loose connection between this ring and the two guiding elements a, that is to say the possibility for these elements to 35 rock about the ring b, enables the elements a to become displaced one with regard to the other in such a manner as to alter the angle which they form with the axis of the cone. This enables the holder to suit different diameters and conical forms of the holders to 40 be fastened and of the holes in the brush-bodies and the like. Further this connection permits a limited relative displacement of the elements a in the direction of their 45 length.

On its lower extremity each guiding-element a is provided with an outwardly extending toothed flange d. With these flanges the handle-holder is put into the bore f pro- 50 vided in the brush-body e or the like. If

now the handle g is driven between the two guiding-elements a, the teeth on said flanges d will be driven into the surrounding wood.

In order to facilitate the removing of the handle, a flange h is formed on the upper 55 end of each guiding-element a. By beating upon this flange with a hammer or the like while the handle is held farther up, this latter is released from the holder. Afterwards the holder may be removed, if desired, by releasing from the wood the teeth of the flange d by forcing the elements a inwardly or towards each other by hammering them on their sides.

In certain cases, for instance with extremely large holders, more than two guiding-elements may be employed. But in general, two will be sufficient.

Instead of providing two eyes c and one ring b, an eye c' may be arranged on each 70 of the two long edges of each guiding element a' and two adjacent eyes of the two elements may be connected by a ring b'. This construction is shown in Figs. 4 and 5.

A ring for the purpose above described 75 may be formed by an endless closed chain.

The eyes c may be formed by making two parallel cuts extending from the top of each guiding-element a downward to a given point and bending outwardly and downwardly that part of the metal lying between these two cuts.

What I claim is:—

A handle-holder for brushes and the like, comprising a plurality of structurally separate guiding elements adapted to be inserted at their inner ends into an opening in the body of the brush and to conjointly form a socket to receive the handle end when so inserted, each element being provided intermediate its ends with an outwardly-projecting, elongated eye; and a ring loosely engaged with said eyes, to constantly connect said elements together while permitting each individual element to rock either inwardly 90 or outwardly upon the ring as a pivot and to move endwise in either direction.

In testimony whereof I have affixed my signature.

JOSEPH SELINGER.
